MULTIUNIT TUBE

Henry E. Fracker, Pasadena, Calif.

Application January 21, 1937, Serial No. 121,507

5 Claims. (CL 250—27.5)

This invention relates to thermionic emission devices; more particularly to a thermionic device that may be utilized for any of several purposes, such, for example, as for providing amplifier, 5 tector, or modulator stages.

Although the present form of tube is especially designed for adaptation in a hearing aid system for deaf or partially deaf persons, yet the principles of construction may readily be utilized for 10 other purposes, such as portable measuring equipment utilizing vacuum tubes, small radio transmitters and receivers designed to be carried by a person, as well as for the radio transmission of data from small weather observation balloons.

15 Heretofore, thermionic emission amplifiers of the usual type have not been suitable for portable hearing aid systems. There are several important considerations in connection with such prior art amplifiers which contribute to their 20 unsuitability.

Chief among these factors is that in all cases the attempt has been made to employ standard radio tubes instead of designing special tubes constructed to meet the very unusual combination of requirements imposed by this particular 25 purpose. Thus, the overall thermionic efficiencies of the complete amplifier circuits of the prior art have been so low that large size batteries had to be used to obtain a life of only a few hours. The 30 size of the batteries coupled with the space occupied by the tubes has been so large that the devices were in no sense adapted to be conveniently and inconspicuously supported on the person having impaired hearing.

35 It is a principal object of the present invention to provide a thermionic tube which makes the construction of a hearing aid system, including all the elements needed to provide an efficient and faithful reproducing system, which is of 40 small size and light weight.

It is another object of this invention to provide a tube which makes possible such a system, by having very low current consumption and thus being capable of operating on very small sized 45 batteries, and without the necessity of frequent renewals.

It is still another object of this invention to provide a multiple section tube wherein a plurality of thermionic emission devices are incorporated in a single envelope.

It is still another object of this invention to provide a tube wherein the tube elements from highly reflecting poorly radiating surfaces focused 55 on the cathode, so that the latter is maintained

at a given temperature with small expenditure of heating battery energy.

It is a still further object to provide a new type of filament for the cathode, which has desirable thermionic emission properties and acts 5 effectively to maintain a more uniform current level in the filament under changing battery voltages, thus assuring long battery and tube life.

It is a still further object of this invention to provide a tube wherein the elements operate at a 10 relatively low temperature, permitting a low ratio of vacuum to enclose a metal surface area and thus enabling the use of an envelope of small size.

It is a still further object of this invention to 15 provide a rugged tube of the character described, in which microphonic or tube noises are minimized by appropriate design of the elements of the tube and of the supports for the cathode.

It is still another object of this invention to 20 provide a multisection tube, wherein the coupling impedances between the sections are enclosed within the tube.

This invention possesses many other advantages, and has other objects which may be made 25 more easily apparent from a consideration of one embodiment of the invention. For this purpose there is shown a form in the drawings accompanying and forming part of the present specification. This form will now be described in detail, illustrating the general principles of the invention; but it is to be understood that this detailed description is not to be taken in a limiting sense, since the scope of this invention is best 30 defined by the appended claims. 35

Referring to the drawings:

Figure 1 is an enlarged elevation, partly broken away, showing the exterior of a tube constructed in accordance with the invention;

Fig. 2 is a fragmentary enlarged longitudinal 40 section through the tube illustrated in Fig. 1;

Fig. 3 is a further enlarged fragmentary section showing in detail a preferred type of construction between tube sections.

Fig. 4 is a sectional view, partly broken away, 45 taken along plane 4—4 of Fig. 2;

Fig. 5 is a sectional view taken along plane 5—5 of Fig. 2;

Fig. 5a is an enlarged fragmentary sectional view, similar to Fig. 5, and showing a detail of 50 construction;

Fig. 6 is a diagrammatic view similar to Fig. 4, but illustrating a modified form of the invention;

Fig. 7 is an elevation of one of the elements utilized in the modification of Fig. 6 for support- 55

ing the structure within the exterior envelope or container forming the tube;

Fig. 8 is a fragmentary sectional view illustrating the manner in which the filamentary cathode is damped;

Fig. 9 is a diagram illustrating a modification in which further supplemental electrodes may be utilized;

Fig. 10 is a diagrammatic longitudinal section illustrating the manner in which a single filamentary cathode is supported and damped; and

Fig. 11 is a diagram of the complete tube illustrating one manner in which the elements of the tube may be connected to form an amplifying system.

A convenient manner in which the enclosing envelope 1 may be made is in the form of a metal or glass tube. This tube 1 may be provided with a small base 2 firmly attached to one end of the tube as by telescoping therewith. This base 2 may be provided with a series of terminal posts, such as indicated at 3 in Figs. 1 and 11. These terminals are made very much smaller and shorter than is customary, because of the relatively minute currents required to operate this multiple tube, resulting in important further reductions in size and weight. By the aid of these terminal posts, connections from the various elements within the tube may be made with an appropriate receptacle.

It is understood that a number of other terminal posts 4 may be supported as shown in the drawings or by another base with pins, at the opposite end of the tube 1, serving as supplemental means for connection to the elements within the tube. These terminal posts may be connected by appropriately sealed in leads to certain electrodes or elements, usually those at the lowest power levels and highest impedances to ground. The interior of tube 1 is usually exhausted to a high degree of vacuum, or it may have a low pressure therein of an inert gas or combination of gases as required by the particular function of the tube.

As illustrated in Fig. 1, the tube 1 is subdivided into a series of sections or units along its length. The left hand end of the tube corresponds to the input side and the right hand end corresponds to the output side. It is preferable for purposes 50 of a hearing aid, that the tube 1 be made as small, as possible. The tube is shown greatly exaggerated in size in Fig. 1. Furthermore the tube units 5, 6, 7 and 8 may progressively increase in axial length, and may each be used for successive 55 stages of amplification of the input impulses received for example, through an appropriate microphone. These units are spaced very closely together so as to utilize as much as possible of the total cathode emission, but are shown widely 60 spaced in the drawings for clarity. The last unit at the right hand end of the tube 1, corresponding to the output stage, is preferably subdivided into two sections 9 and 10 which may be in push-pull 65 relation. These two output sections 9 and 10 may advantageously be constructed as a push-pull class B or C stage, thereby reducing the drain of current from the source of electrical energy providing the anode currents. The push-pull arrangement will, as is well understood, result 70 in substantial neutralization of the even harmonics which are necessarily present in these classes of amplifiers. Further reduction in distortion caused by the output stage of high plate 75 circuit efficiency may readily be accomplished by

providing a single or preferably multistage reverse feedback circuit.

Since economy of space, weight and electrical energy is of paramount importance in the use of hearing aids adapted to be supported on the person utilizing the system, the dimensions of tube 1 are reduced to the lowest practical value. Since the output power required of a hearing aid is relatively small, the plate battery potential is conveniently kept to low values, enabling very 10 large reductions in size and spacing of tube electrodes to be made, as the minimum spacing need not be determined by the presence of usual high potential differences within the tube. This large reduction in tube size results in the further advantage that the electrical energy needed to maintain the required thermionic emission from the cathode may be reduced. Hence, without sacrificing battery life, the cathode heating battery may also be greatly decreased in size and 20 weight; the decrease being very much greater than simply in proportion to the reduction in tube dimensions.

One adverse effect of reducing the dimensions of a tube of the usual prior art construction is 25 the large end effect emission loss of the filamentary cathode, due to the cooling of considerable lengths of the filament adjacent to the terminals and points of contract with tension springs. In short filaments the ratio of useful, 30 or actively emitting, filament length to total filament length becomes very low, and any attempt to improve this ratio by operating the filament at an increased temperature results in a most unsatisfactory tube life, with heavy replacement 35 costs. All of these heat losses in the usual filament structure necessitate the use of large batteries for a reasonable life. However, by maintaining a single filament at practically uniform 40 temperature throughout its length except for short distances adjacent to the two ends, a very much higher thermionic efficiency can be realized than in the ordinary prior art cathode structure, 45 in which the temperature changes from ambient to about 900 degrees C. as many as 15 times in a five stage amplifier. Thus in the present construction, unusual thermionic efficiency is achieved by utilizing a single elongated filamentary cathode 11, which extends axially through all of the tube units 5, 6, 7, 8 and 9-10. Further 50 advantages derived from the use of a single filamentary cathode of this sort will be referred to hereinafter.

In order to support the filament 11, as well as other electrodes within the tube envelope 1, use 55 is made of a framework structure which will now be described.

The framework in general comprises four longitudinally disposed parallel metallic rods 12, 13, 14 and 15 (Figs. 2, 3, 4 and 5). These four rods 60 are held in appropriate relative positions by the aid of metal shielding plates 16, spaced along the length of the tube 1 and placed between the units 5, 6, 7, 8, 9, and between sections 9 and 10. These plates are supported in any appropriate manner, one form of which is shown to best advantage 65 in Figs. 3 and 4. Thus, for example, these plates 16, as shown most clearly in Fig. 4, may each be provided with four radial ears 17. These ears are formed with appropriate apertures for the 70 passage of the rods 12, 13, 14 and 15. On opposite sides of each of the ears 17 are disposed a pair of metal bushings 18, as shown in Fig. 3, also telescoping respectively over the rods 12, 13, 14 and 15. These metal bushings may be spot weld- 75

ed to the rods, as well as to the plate 16. The ears 17 may be folded over, as illustrated in Fig. 3, to contact one of the bushings 18 where the ear may also be spot welded to that bushing.

5 Of course, the operation of assembling this framework with the plates 16 must occur in succession after the tube units, except for the filament 11 are assembled. The plates 16 are each provided with a sufficiently large central aperture 19 for the insertion of the filament 11 after all 10 of the units are otherwise assembled. The shielding plates 16 are all maintained at practically ground potential by welding a lead inside the tube to one of the rods 12, 13, 14 or 15, and to the filament terminal 27 shown in Fig. 10, adjacent to the input section.

The framework comprising the rods 12, 13, 14 and 15 as well as the plates 16 with their supporting members, is arranged to be frictionally supported with respect to the internal surface 20 of the tube 1. In the form shown in Figs. 2, 3, and 4, this frictional support is provided adjacent to each plate 16 by the aid of a pair of supporting insulation plates 20 and 21. These plates may 25 be conveniently formed of mica. They may be supported on the bushings 18 as by having apertures in alignment with these bushings and of such size that they may be placed upon the reduced portions 22 of these bushings. The ends 30 of the bushings 18 may then be upset as shown at 23, to clamp the plates 20 and 21 onto the bushings. Adjacent to the periphery of each of the plates 20 and 21 are a series of serrations or teeth 24 adapted frictionally to contact the internal surface of the tube 1. The mica plates 20 and 21 have sufficient give or resilience so that the points of the teeth 24 are urged resiliently against the interior surface of the tube 1, to maintain the framework structure within the tube 40 against motion.

The diagram, Fig. 10, illustrates the spacing of the intermediate metal shielding plates 16. The thick mica end supporting insulation plates 25 and 26 are also fastened to the rods 12, 13, 45 14 and 15 by means of metallic bushings similar to 18. Between these terminal insulation plates, the filament 11 may be stretched; for example, the left hand end of filament 11 may be welded to a terminal piece 27, in turn riveted or clamped to a terminal piece 28, over the central aperture in the terminal insulation plate 25. The right hand end of cathode 11 50 may be welded to a spring support terminal 28, in turn fastened as by riveting or clamping to the terminal insulation plate 26. The spring support 55 28 causes a constant tension to be applied to the cathode 11, keeping it sufficiently taut even when the filament is heated by the passage of the heating current. Appropriate connections may be made to the terminal piece 27 and spring 60 terminal 28 for placing the cathode 11 in series with a source of electrical energy, such as a small filament heating dry battery.

The combined terminal and tension spring 28 is located adjacent to the output rather than the 65 input stage of the tube. In this way the greater part of the longitudinal movement of the filament, due to thermal expansion prior to reaching normal operating temperature, will occur in the high level stages of the tube rather than in the 70 input or low level stages. By means of this expedient, any noises in the form of slight electrical voltage variations attendant upon expansion of the filament will be rendered practically 75 inaudible in the output of the tube, since rela-

tively little amplification follows that part of the filament having significant displacement.

In order to damp the filament 11 against microphonic vibrations, damping means are provided on each of the shielding plates 16. This 5 damping arrangement is disclosed most clearly in Figs. 2 and 4.

Thus, mounted upon one side of plate 16 is an insulation segment 29 having low thermal conductivity, preferably formed of very thin mica. 10 This segment is arranged concentrically with the filament 11 and provides a concave arcuate seat for the filament. On the opposite side of each plate 16, an insulation bar 30, also preferably made of thin mica, is pivoted about a pin 31 fastened to the plate 16. After the filament 11 is threaded through all of the central apertures in plates 16, 20, 21, 25 and 26, and is stretched taut between its terminals 27 and 28, and before insertion of the framework in the tube 1, the mica bars 30 can be swung into the damping position in contact with the filament, illustrated in Fig. 4. It may be held in the damping position by the aid of a small metal clip 32, which can be spot welded to the plate 16. It is understood that the 15 filament may move lengthwise through the damping means, to allow for expansion and contraction from temperature changes.

In place of the notched mica discs 20 and 21 20 30 for positioning the framework within the tube 1, another type of support may be provided as illustrated in Figs. 6 and 7. In this form of the invention the supporting bars 12, 13, 14 and 15 are provided as before. Fastened to each of them 25 are two or more mica members 33 of normally flat form. This fastening may be accomplished by the aid of a small rivet 35 passing through the center of member 33 and spot welded to the respective supporting bars. It is apparent that 35 prior to insertion of the framework into tube 1, the members 33 are in the flat form shown for example as 34 in the right hand portion of Fig. 6. However, as the framework is inserted into tube 1, these members 33 assume an arcuate form 40 in order that their end edges may pass into tube 1. The resilience of these plates maintains the framework frictionally within the tube. In order to facilitate the insertion of the members 33 into the tube, the leading edge of each of the 45 members 33 may be rounded as shown at 33' in Fig. 7. Thus as the completed framework structure is inserted within the tube 1, these rounded surfaces first contact with the interior surface 50 of the tube, and are then later automatically distorted on further axial movement within tube 1, to conform to the arcuate form shown in Fig. 6.

The various tube elements for each of the units 5, 6, 7 and 8 and each of the sections 9 and 10 may readily be supported from the mica plates 60 20, 21 as shown most clearly in Figs. 2, 3 and 4. Thus, the innermost grid electrode 36, which may be in the form of a helix may be telescoped over and welded to a pair of supporting rods 37 and 38. These rods are supported at their ends on 65 bushings 39. This structure is shown most clearly in Fig. 2. These bushings 39 may be spot welded to the rods 37 and 38 and may have reduced portions extending through appropriately formed apertures within the mica plates 20 and 21. As 70 illustrated clearly in Fig. 3 these reduced portions may be upset prior to being welded to the support rods, for attaching the bushings 39 firmly to these mica plates.

One or more supplementary grids may also be 75

similarly supported in each tube unit or section. In the form shown in Figs. 2 and 5, there is an additional supplementary grid 40 supported on the rods 41.

5 In Fig. 9, a series of concentric grid electrodes is indicated in which there are several additional supplementary grids such as 42 and 43. The specific number of such supplementary grids, used for example as suppressor, screen or space 10 charge grids, is immaterial so far as the present invention is concerned. They may all be appropriately supported in a concentric manner, by the aid of supporting elements such as those just described.

15 A problem of particular importance to the user of a portable vacuum tube hearing aid having large amplification, as well as for certain other applications, is that of undesired microphonic response of the tube to unavoidable mechanical agitation. Since such mechanical agitation is converted into electrical voltage variations and amplified as such, the major microphonic disturbances arise in the input and low level stages as these are followed by considerable amplification. Microphonic response is almost entirely due to a mechanical shock setting tube elements, principally the filament and control grid wires into relatively undamped vibration. Since rigidity of the tube grids and damping of the filament 20 are the only effective remedies for undue microphonic response, it is clearly seen that with the aid of the present invention, the tube herein described possesses an extremely low microphonic response. This is achieved, not only by the usually rugged construction, involving in part the riveting and welding of all tube elements and their supports, but also by the reduction in size 25 of tube elements and by proportioning the length of each section according to the power level of 30 amplified voltages to be handled. Thus all the elements including the filament, of the most microphonically important section of this tube, the input stage, are inherently especially rigid because it is the shortest of all the sections, being 35 required to handle only the minute input power. The following low level section is somewhat less rigid because of its greater length, but since considerably less amplification follows it, its microphonic response is much less important.

40 If unusually severe conditions of mechanical vibration or shock, coupled with the necessity for increased amplifier gain, are encountered, additional damping elements for the filament and an increased number of support rods for the grids 45 may readily be provided in the first few low level tube sections. The filament damping elements are shown in Figs. 8 and 10, and may comprise a very thin transverse bar 44, of insulation having extremely low thermal conductivity, such as 50 mica. Each of these bars may be notched as indicated at 45 for the reception of the cathode 55 46, and they may be held firmly in place upon the internal grid supporting rods 37 and 38. The extra grid support rods, to which the individual 60 grid wires are welded in the usual manner, may be arranged as shown at 38' in Fig. 5.

65 Each of the units 5, 6, 7 and 8 as well as each of the sections 9 and 10 is further provided with a plate or anode. This plate or anode is conveniently made in the form of a cylindrical metallic element 46, extending the full length of each unit or section between the mica plates 20 and 21, instead of being somewhat shorter, as shown in Fig. 2 for clarity. It may be attached 70 rigidly to the rods 47 extending between the mica

75 plates 20 and 21 of each unit or section and appropriately supported as heretofore described in connection with the other rods 37 and 38.

The leads from the base terminals and coupling elements to the tube electrodes may appropriately 5 consist of small but rigid wires 48 and 48' passing intermediate the ears 17 and tightly through holes in the mica plates 20 and 21, as shown in Figs. 4 and 5. In case of the few low level or high 10 impedance leads, shielding may be provided by welding lengths of thin walled metallic tubing to the support rods 12, 13, 14 and 15, and passing each of these leads through separate lengths of the tubing, as shown at 62 and 63 in Fig. 5. The 15 ratio of tubing inside diameter to lead diameter 15 is kept large to minimize capacity effects. In the case of long sections where the distance between the lead supports 20 and 21 becomes large, microphonic effects due to capacity changes between lead and shield may be kept low by providing one 20 or more tightly fitting insulating members within the tubing to rigidly support and damp the lead 25 against vibration.

The special internal coupling condensers, employing the anode of each unit or section as 25 one plate, are constructed in the following manner. As illustrated most clearly in Figs. 2 and 5, each cylindrical plate 46 may be overlaid with a very thin tubular dielectric member 49 of mica or similar material possessing a large dielectric 30 constant, low dielectric absorption, and excellent volume resistivity and mechanical properties at high temperatures. Disposed over this layer of dielectric material is another tubular conducting element 50 forming the other plate of the condenser. If the capacity is still insufficient for 35 certain purposes, or additional electrical shielding is desired, a supplemental thin tubular layer of dielectric 51 such as mica, may be disposed over the tubular member 50; and over this dielectric tube 51 may be disposed another tubular 40 metallic member 52. The anode 46 and the external tube 52 may be electrically joined together as by the lead 53 to form one plate of a condenser. The metallic cylinders may be provided 45 with polished copper surfaces to retain within the tube as much as possible of the heat radiated by the cathode.

Furthermore in order to permit expansion of the plates upon temperature rise, as encountered 50 in the induction furnace during outgassing of the tube, without undue straining of the material, the tubular metallic elements 50 and 52 may be formed in the manner illustrated most 55 clearly in Fig. 5. It is there seen that each of the tubular plates 50 and 52 is formed of a flat sheet bent in cylindrical form with radial extensions, such as 54, 54' that are in contact along their outer longitudinal edges only. The metallic plates 50 and 52 may be maintained in cylindrical 60 form by spot welding the outer longitudinal edges of these flanges 54 and 54'. A slight degree of resilience of these tubular elements is provided by this construction, allowing the necessary slight expansion and contraction.

In cases where the tube must be operated under 65 conditions necessitating the maintenance of an extremely high vacuum within the tube throughout its life, it is desirable to form the anode 47 as well as the tubular metallic elements 50 and 52 70 of a previously de-gassed metal such as tantalum, which is capable of freely absorbing very large volumes of gas at only red heat. Thus, if any slight amount of gas is trapped during the manufacture between the elements forming the cou- 75

pling condensers, it will readily be absorbed by the adjacent tantalum surfaces when the tube is subjected to the induction furnace during evacuation and de-gassing. Since the gas absorbed at red heat by the tantalum is not released except at very much higher temperatures, far above the highest possible instantaneous temperatures attained by the tube in operation, a very high degree of vacuum is easily maintained during tube life. The conventional "getter" may also be utilized in the usual manner, to decrease the necessary pumping time for each tube.

It is desirable to utilize resistance coupling between the amplifier units. These resistances are of comparatively high order, and may conveniently take the form of molded ceramic covered tubular rods or elements having low temperature resistance coefficient and occupying very small space. They may be included inside the tube envelope 1. One of them for the tube unit shown in Figs. 2 and 5 is illustrated at 55. Metal clamps 56 may compass the ceramic resistor 55 and may be joined as by welding to one of the framework rods such as 12.

Fig. 11 illustrates how the coupling resistors 55 and the capacities 46-50-52 may be joined in appropriate manner to provide the coupling between the stages. The common filament 11 is shown as having terminals comprising one of the terminals 3 and one of the terminals 4 at opposite ends of the tube. Some of the resistors 55 are shown connected to a common lead 56 and others to a common lead 57. The last stage includes the push-pull arrangement with a pair of plates 58 and 59. The circuit of the push-pull stage may be completed exteriorly to the tube 1.

As heretofore stated the cathode 11 forms a single source of electrons for all of the units and sections. It is usual to provide bias potentials for the control grid electrodes 36 negative with respect to the negative end of that part of the cathode 11 passing through the particular section specified. The negative grid bias in the present instance can be readily obtained for all sections (other than the input, which for some purposes does not require a biasing potential) without the need of any extraneous source of electrical energy or potential, provided care is exercised in the manufacture of the tube to keep effective contact potentials to very small values. The negative bias potentials are secured by connecting the negative lead of the filament battery, which is also grounded, to the filament terminal adjacent to the input stage, and then connecting all grids 50 to this negative filament terminal through appropriate grid impedances. In this way, the grid bias of the tube sections progressively increases from input to output of the tube in accordance with the demands of the similarly increasing power 60 levels of the amplified voltages; each section being biased more negatively than the foregoing one by an amount equal to the filament potential drop of the preceding section. Each section is specially designed to operate most efficiently with the 65 particular value of grid bias potential derived for it in this manner.

The problem of providing long life for the batteries for operating the system is adequately met with the aid of the present construction. Economy, for example, is secured by the fact that the electrodes in the tube structure are very small and closely spaced. Therefore they require somewhat lower potential differences for the same degree of amplification. Furthermore the cathode 75 11 requires very much less electrical energy to

obtain the desired thermionic emission. The close spacing of electrodes provides a high amplifier gain, decreasing the number of stages necessary for a specified amplification and thereby reducing cathode and plate battery drains.

A saving in energy for heating the cathode is effected, as previously indicated, by providing a cylindrical anode structure which surrounds the grids and cathode. The inner and outer surfaces of the anode are made reflecting so that heat radiated from the cathode is reflected back and focused on the concentrically located cathode instead of being re-radiated out of the tube. The reflecting outer surface of the anode, being a poor radiator, likewise aids in retaining the cathode energy within the tube. The surfaces of the grid wires may also be arranged to reflect the heat back to the cathode by winding the cylindrical grids with narrow flat ribbon instead of round wire and providing the ribbon with an effective heat reflecting surface. Both surfaces of the metallic shielding plates between all of the tube units are also provided with reflecting surfaces. Polished copper surfaces may be used for all heat reflecting and radiating surfaces within this tube since the special cathode operates at very low temperatures, therefore radiating most of its energy at wave-lengths where polished copper forms approximately the most efficient reflector.

In order further to reduce the drain from the filament battery, the filamentary cathode 11 is constructed in a special manner. It is apparent that when a new cathode heating battery is installed, the potential difference developed across its terminals is somewhat larger than after it has been in use for a time. If no regulating resistance is used (as is preferred in order to conserve battery energy and render unnecessary any manual adjustment) then the current drain through the usual Kone, other nickel alloy or platinum-iridium filament during this first period of battery life is relatively heavy, with an attendant reduction in useful life of both battery and tube.

By a special construction of the cathode, the use of a regulating resistance is obviated, and yet the current drain is prevented from rising to abnormal values during the first period of operation with a fresh battery.

For this purpose, the cathode 11 is built up of a core made from some material having a very high temperature resistance coefficient at the temperature of operation. Therefore its resistance increases greatly with rise in filament temperature, and therefore with increase in filament current. Such a core is preferably tungsten for small diameter filaments requiring high tensile strength at operating temperatures, although iron might be used in certain cases. Thus, any tendency for the current in the filament to increase is largely offset by the increase in resistance of the filament. Likewise, as the heating battery decreases its potential with use, the resistance of the filament also falls, tending to keep the filament current and therefore emission, much more constant. Thus not only is the amplifier gain and output power capacity maintained over a longer period of battery life, but a larger proportion of the total energy within the battery is extracted before its life is terminated.

In order to improve the thermionic emitting qualities of the cathode, the core is preferably coated with an extremely thin layer of copper, upon which is vaporized or otherwise deposited a small amount of aluminum forming an alloy

with the copper. The alloy of copper and aluminum thus exposed, after being coated with the appropriate metallic oxides, forms a thermionic emitting surface possessing a very high thermionic efficiency at unusually low operating temperatures. Since even small decreases in operating temperature effect very large decreases in radiation energy losses, correspondingly large reductions in heating battery consumption are obtained, thus enabling long life to be secured from very small size, light weight batteries.

The mode of assembly of the tube 1 is apparent from the foregoing. The framework including the rods 12, 13, 14 and 15 is first assembled upon one of the end plates 25 or 26, then each previously assembled section or unit is assembled in succession upon these rods. The filamentary cathode 11 however, is not threaded through the plates 16, 20, 21, 25 and 26 until all of the tube sections are assembled on the framework rods.

Next the damping elements 30 are placed in operative relation with cathode 11. If the intermediate dampers 44 are required, they are placed inside their respective inner grids as each section 25 is assembled, and prior to the insertion of the cathode 11.

After the cathode 11 is installed, the completed framework with its units and sections may be inserted inside tube 1. The leads are then brought out through the tube and the process 30 of outgassing can then be proceeded with. After this, the tube may be sealed off and the base 2 and terminals 4 installed. Following suitable aging of the filament, the tube is then ready for 35 operation.

What is claimed is:

1. In a thermionic emission device, a sealed container, an elongated cathode in the container, a series of sets of spaced electrodes cooperating 40 with the cathode to form separate thermionic emission units, each set having an anode and a control electrode surrounding the cathode, and a conducting member within the container cooperating with the anode to form a coupling capacity between the anode and the control electrode of the succeeding unit.

2. In a thermionic emission device, a sealed container, a cathode in the container, a plurality of sets of electrodes spaced lengthwise with respect to the cathode and forming therewith a series of separate thermionic emission units, each 5 of said sets having an anode, a plurality of coupling resistors in the container, and a plurality of means within the container cooperating respectively with the anodes to form coupling capacities.

3. In a thermionic emission device, a sealed 10 vessel, a filamentary cathode in the container, a plurality of sets of electrodes arranged along the length of the cathode and cooperating therewith to form thermionic emission units, and arranged in succession to operate upon impulses 15 first affecting the first set at the input side of the vessel, and finally affected by the last of the sets at the output side of the vessel, means for rigidly securing the cathode adjacent the input side of the vessel, and resilient means for tensioning the cathode adjacent the output side of the vessel.

4. In a thermionic emission device, a sealed container, a cathode in the container, an anode surrounding the cathode, a conductor electrically 25 connected with the anode, and extending over the outer surface of the anode, and forming therewith an element of a coupling capacity, and an intermediate conductor between the anode and the other conductor, to form the other element 30 of the coupling capacity.

5. In a thermionic emission device, a sealed container, an elongated cathode in the container, a plurality of electrodes surrounding the cathode and spaced lengthwise with respect thereto, apertured members spaced along the cathode, said 35 apertures having considerable clearance with respect to the cathode, said cathode extending through the apertures, seats respectively on said members for the cathode formed of material of 40 low electrical and thermal conductivity, bars pivoted respectively on the member and adapted to hold the cathode on said seats, and means to maintain the bars in said holding positions.

HENRY E. FRACKER.
